UNITED STATES PATENT OFFICE

HERMAN MOLNER, OF CHICAGO, ILLINOIS

DESIGN FOR A PICTURE FRAME

Application filed October 4, 1928. Serial No. 28,369. Term of patent 3½ years.

To all whom it may concern:

Be it known that I, HERMAN MOLNER, a citizen of the United States, residing at Chicago, in the county of Cook and State of Illinois, have invented a new, original, and ornamental Design for Picture Frames, of which the following is a specification, reference being had to the accompanying drawing, forming part thereof, in which—

Figure 1 is a front view of a picture frame showing my new design, and Figure 2 is a section on the line 2—2 of Figure 1.

I claim:

The ornamental design for a picture frame, as shown.

In witness whereof I affix my signature.

HERMAN MOLNER.
